RETRACTING TYPE THEATER CHAIR

Merritt K. Orton, Grand Rapids, Mich., assignor
to American Seating Company, Grand Rapids,
Mich., a corporation of New Jersey

Application June 29, 1946, Serial No. 680,425

4 Claims. (Cl. 155—116)

1

The present invention relates to chairs and more particularly to chairs of the retracting type for installation in theaters, auditoriums and the like.

The primary objects of the invention are to provide an improved chair of the retracting type wherein the occupant may move the seat rearwardly in order to permit others to pass in front of him without his having to rise from his seat; to provide such a chair which when retracted utilizes a minimum of space to the rear; to provide such a chair having an arrangement of pivoted links for supporting the seat and back and which arrangement provides for easy and comfortable retracting and forwardly returning movements; to provide such a chair whose mountings and operating mechanism are located below the seat level and which are therefore concealed from view; and in general to provide such a retracting chair which is quiet and efficient in operation and attractive in appearance.

Illustrative embodiments of the invention are shown in the accompanying drawings, wherein:

Figure 1 is a perspective view of a retracting theater chair in its forwardly moved position;

Figure 2 is a sectional view thereof taken on line 2—2 of Figure 3 and showing the parts of the chair in their forwardly moved positions;

Figure 3 is a fragmentary front elevational view of the right hand side of the chair;

Figure 4 is a perspective view of the chair similar to Figure 1 and showing the chair in its rearwardly moved or retracted position; and

Figure 5 is a fragmentary sectional view similar to Figure 2 and showing the parts of the chair in their rearwardly moved or retracted positions.

Referring now in detail to these drawings, the retracting chair there shown is mounted upon a frame which comprises spaced upright chair supporting standards 10 here shown rigidly connected by a cross-brace 11 and provided with conventional arm rests 12. If desired the standards may be secured directly to the floor and may have no connection other than the chair parts hereinafter described, and the term "frame" as used herein is intended to include such an arrangement of the standards.

The chair proper generally comprises a seat and back assembly in which the seat 13 and back 14 are pivotally connected for relative movement, and this assembly is so mounted on the standards that when the seat moves rearwardly the back also moves rearwardly and simultaneously turns from its inclined position to a near-vertical position. In addition the seat 13 is preferably

2

independently turnable about a horizontal axis so that it may be raised for facilitating sweeping under the chair.

The chair back 14 is secured as by screws or bolts 15 to the inwardly turned flanges 16 of back carriers 17 on opposite sides of the chair. The forward ends of the back carriers 17 are supported by front supports 18 to the upper ends of which said back carriers are pivotally connected. The lower ends of the front supports 18 are pivotally associated with the standards 10 by means of members 19 having their forward ends pivoted about a horizontal axis to the front supports 18 and their rearward ends pivoted about 15 a vertical axis to lugs 20 on the standards to thus compensate for variation in the distances between standards.

The back carriers 17 are supported in the rear by several pairs of links, in which the links 21 of the first pair have their upper ends pivotally connected to members 22 pivoted about a vertical axis to the standards 10 similarly to the members 19. The links 23 of the second pair of rear supporting links have their lower ends pivotally connected to the lower ends of the links 21 and have their upper ends pivotally connected to the rear of the back carriers 17. The links 24 of the third pair of rear supporting links have their rearward ends pivotally connected to the links 21 and 23 at their point of connection and have their forward ends pivotally connected to the front supports 18. It will be seen that by this arrangement a floating support, i. e. the links 23, is provided for the back carriers 17.

35 Seat carriers 25 have their rearward ends pivotally associated with the back carriers 17, being pivotally connected to the back carriers and to the upper ends of the links 23 at their point of connection. The seat carriers 25 are supported in the front by short links 26 which links 26 are pivotally connected at their upper ends to the front supports 18 and are pivotally connected at their lower ends to the forward ends of the seat carriers. By this arrangement the forward 40 and rearward movement of the seat carriers is in a substantially horizontal path. The chair seat 13 is mounted for turning movement about a horizontal axis by means of seat arms 27 secured on opposite sides of the seat by screws 28 and 45 pivotally connected by any conventional means at 29 to the seat carriers 25 respectively. The seat 13 is supported in its lowered position of occupancy by contact of the seat arms 27 with inwardly extending stops 30 on the seat carriers 50 25.

Movements of the seat and back when retracted or returned by the chair occupant, are best understood by a comparison of Figures 2 and 5 of the drawings. It will be seen that the seat moves rearwardly and forwardly with the seat carriers in a substantially horizontal path during which movement the back moves rearwardly with the back carriers and assumes a near-vertical position thus to utilize a minimum of space to the rear of the chair.

Retracting movement of the chair is stopped by the contact of bumpers 31 on the links 24 with the upper ends of races 32 in the front supports 18 as seen in Figure 5; and forward returning movement of the chair is stopped by contact of the bumpers 31 with the lower ends of the races 32 as seen in Figure 2. The front supports 18 are preferably connected by a cross-tie or strut 33 secured thereto as by welding, and the stability of the structure is thereby increased. While but one specific embodiment of the invention has been herein shown and described, it will be understood that numerous details may be altered or omitted without departing from the spirit of the invention as the same is defined by the following claims.

I claim:

1. In a chair, a frame, back carriers and a back mounted thereon, front supports having their lower ends pivotally connected to the frame and their upper ends pivotally connected to the lower forward ends of the back carriers, seat carriers having their rearward ends pivotally connected to the back carriers and their forward ends pivotally connected to the front supports, a seat mounted on the seat carriers, and means for supporting the rearward ends of the back carriers comprising pairs of links, the links of the first pair having their upper ends pivotally connected to the frame, the links of the second pair having their lower ends pivotally connected to the lower ends of the first pair and their upper ends pivotally connected to the rearward ends of the back carriers, and the links of the third pair having their rearward ends pivotally connected to the links of the first and second pairs and their forward ends pivotally connected to the front supports, stops on the front supports, and means carried by the third pair of links adapted to contact said stops to limit the forward and rearward movements of the front supports.

2. In a chair, a frame, back carriers and a back mounted thereon, front supports having their lower ends pivotally connected to the frame and their upper ends pivotally connected to the lower forward ends of the back carriers, seat carriers having their rearward ends pivotally connected to the back carriers, links pivotally connected at their upper ends to the front supports and pivotally connected at their lower ends to the forward ends of the seat carriers, a seat mounted on the seat carriers, and means for supporting the rearward ends of the back carriers comprising pairs of links, the links of the first pair having their upper ends pivotally connected to the frame, the links of the second pair having their lower ends pivotally connected to the lower ends of the first pair and their upper ends pivotally

connected to the rearward ends of the back carriers and the links of the third pair having their rearward ends pivotally connected to the links of the first and second pairs and their forward ends pivotally connected to the front supports, stops on the front supports, and means carried by the third pair of links adapted to contact said stops to limit the forward and rearward movements of the front supports.

3. In a chair, a frame, back carriers and a back mounted thereon, front supports having their lower ends pivotally connected to the frame and their upper ends pivotally connected to the lower forward ends of the back carriers, seat carriers having their rearward ends pivotally connected to the back carriers and their forward ends pivotally connected to the front supports, a seat mounted on the seat carriers turnably about a horizontal axis, means on the seat carriers for supporting the seat in its lowered position of occupancy, and means for supporting the rearward ends of the back carriers comprising pairs of links, the links of the first pair having their upper ends pivotally connected to the frame, the links of the second pair having their lower ends pivotally connected to the lower ends of the first pair and their upper ends pivotally connected to the rearward ends of the back carriers, and the links of the third pair having their rearward ends pivotally connected to the links of the first and second pairs and their forward ends pivotally connected to the front supports, stops on the front supports, and means carried by the third pair of links adapted to contact said stops to limit the forward and rearward movements of the front supports.

4. In a chair, a frame, a seat and back assembly wherein the seat and back are pivotally connected for relative movement, front supports having their lower ends pivotally connected to the frame and their upper ends pivotally connected to the forward part of the seat and back assembly, and means for supporting the seat and back assembly in the rear comprising pairs of links, the links of the first pair having their upper ends pivotally connected to the frame, the links of the second pair having their lower ends pivotally connected to the lower ends of the first pair and their upper ends pivotally connected to the rearward part of the seat and back assembly, and the links of the third pair having their rearward ends pivotally connected to the links of the first and second pairs and their forward ends pivotally connected to the front supports, stops on the front supports, and means carried by the third pair of links adapted to contact said stops to limit the forward and rearward movements of the front supports.

MERRITT K. ORTON.
